CLAIM

The ornamental design for a vertical electrical connector, as shown and described.

DESCRIPTION

FIG. 1 is a top, left, and rear perspective view of a first embodiment of a vertical electrical connector showing our new design;

FIG. 2 is a bottom, left, rear perspective view thereof;

FIG. 3 is a top, left, front perspective view thereof;

FIG. 4 is a bottom, right, front perspective view thereof;

FIG. 5 is another top, left, rear perspective view thereof;

FIG. 6 is another bottom, right, front perspective view thereof;

FIG. 7 is a rear elevation view thereof;

FIG. 8 is a front elevation view thereof;

FIG. 9 is a bottom plan view thereof;

FIG. 10 is a top plan view thereof;

FIG. 11 is a right side elevation view thereof;

FIG. 12 is a left side elevation view thereof;

FIG. 13 is a top, left, and rear perspective view of a second embodiment of a vertical electrical connector showing our new design;

FIG. 14 is a bottom, left, rear perspective view thereof;

FIG. 15 is a top, left, front perspective view thereof;

FIG. 16 is a bottom, right, front perspective view thereof;

FIG. 17 is another top, left, rear perspective view thereof;

FIG. 18 is another bottom, right, front perspective view thereof;

FIG. 19 is a rear elevation view thereof;

FIG. 20 is a front elevation view thereof;

FIG. 21 is a bottom plan view thereof;

FIG. 22 is a top plan view thereof;

FIG. 23 is a right side elevation view thereof; and,

FIG. 24 is a left side elevation view thereof.

The broken line portion of the figure drawings is included to show unclaimed subject matter only for the purpose of illustrating environment and forms no part of the claimed design.
